UNITED STATES PATENT OFFICE.

ARNOLD STUCKI, OF ALLEGHENY, PENNSYLVANIA, ASSIGNOR TO STAND-ARD STEEL CAR COMPANY, OF PITTSBURG, PENNSYLVANIA, A CORPORATION OF PENNSYLVANIA.

METALLIC UNDERFRAME FOR PASSENGER-CARS.

No. 824,084.

Specification of Letters Patent.

Patented June 19, 1906.

Application filed October 24, 1902. Serial No. 128,645.

To all whom it may concern:

Be it known that I, ARNOLD STUCKI, a citizen of the United States, residing at Allegheny, in the county of Allegheny and State of Pennsylvania, have invented a certain new and useful Improvement in Metallic Underframes for Passenger-Cars, of which the following is a full, clear, and exact description.

10 The object of this invention is to provide a metallic underframe for railway passenger-cars, and especially to utilize pressed-steel shapes in the construction of such underframes, and while it is preferred to use pressed-steel shapes it is to be understood that such shapes may be replaced wholly or in part in the present invention by rolled or other commercial shapes or castings.

15 In carrying out the invention by means of 20 pressed-steel shapes there are used longitudinal sills, some or all of which may be bellied, as in the common freight-car construction, and the center sills are extended continuously from end to end of the car and beyond the 25 end sills proper and are supplied with face-plates of novel construction, said face-plates being connected with bolsters by auxiliary longitudinal sills and the bolsters being framed in the underframe. These face-

30 plates may be utilized to receive parts of the vestibules. The side sills extend above the center sills and body-bolsters and have applied to them externally wooden stringers, which, with other stringers laid upon the bolsters 35 and intermediate transoms or diaphragms, receive the wooden flooring, and the side sills are set in from the sides of the cars, so as to be as inconspicuous as possible. The end sills are composed of flanged sections secured

40 between the various longitudinal sills and covered by top and bottom plates. The ends of the car are constructed with easily-interchangeable parts, so as to provide for ready repairs.

45 In the accompanying drawings, illustrating the invention, in the several figures of which like parts are similarly designated, Figure 1 is a top plan view and partial horizontal section of one end of the car. Fig. 2 is a side 50 elevation. Fig. 3 is an end view of the face-plate. Fig. 4 is a transverse section through the bolster. Fig. 5 is a front elevation of the end sill. Fig. 6 is a top plan view of the end

sill. Fig. 7 is a bottom plan view of the end sill. Fig. 8 is a cross-section of the end sill, taken substantially in the plane of line A B, 55 Fig. 5. Fig. 9 is a top plan view of the face-plate. Fig. 10 is a bottom plan view of the face-plate. Fig. 11 is a transverse section of the face-plate, taken substantially in the 60 plane of line C D, Fig. 9.

The side sills 1 in the preferred construction are bellied, as indicated in Fig. 2, so as to serve not only as such sills, but also to take the place of usual truss-rods, and these 65 side sills extend, by preference, continuously from end sill to end sill of the underframe. The center sills 2 may be of uniform cross-section or bellied, as preferred, and these center sills extend continuously from end to end 70 of the frame and beyond the end sills. The several longitudinal sills are connected by body-bolsters built in between them and comprising, essentially, pairs of flanged dia- 75 phragms 3, arranged between the side sills and the center sills, and other flanged dia- phragms 4, arranged between the center sills, together with top and bottom cover- 80 plates 5 and 6, respectively, riveted to the flanges of the pairs of diaphragms.

Auxiliary longitudinal sills 7 are secured to the bolsters and project thence beyond the ends of the end sills. Flanged diaphragms or braces 8 are interposed between the side sills, auxiliary sills, and center sills in order 85 to tie these parts rigidly together.

The end sills are made up of flanged dia- 90 phragms 9, interposed between and riveted to the various longitudinal sills and supplied with top and bottom cover-plates 10 and 11, respectively.

A face-plate 12 is mounted upon the aux- 95 illary sills 7 and upon bars 13, spliced to the center sills, and these splice-bars are used so that in case of damage to the ends of the car repairs may be more readily made than would be possible were the center sills ex- 100 tended entirely out to the face-plates. The face-plate in the preferred construction is of pressed steel, so as to be readily interchange- 105 able, and it has a vertical wall 14, tapering toward the ends 15, and a protruding central portion 16, recessed below at 17, so as to provide for the reception of the coupling, and not only does the face-plate taper from a perpendicular plane, but it also tapers from a

horizontal plane, as indicated, respectively, in Figs. 1, 3, 9, and 10. The outer ends 15 may be reinforced by angle-bars 18. The top flange 19 and bottom flange 20 are of considerable width, so as to obtain stiffness, 5 cover in the ends of the longitudinal sills with which the face-plate is connected, and also to afford room for the erection of the vestibules. The face-plate takes the place 10 of the two heavy timbers formerly used in wooden vestibules. It receives the brake-mast and forms a finish for the end of the car. The top flange of the face-plate forms a convenient place upon which to rivet the 15 four uprights of the vestibule front wall, thus making the shifting of the front wall well nigh impossible. This top flange also forms a medium to receive one side of the steps, the other side being secured to the end 20 wall. The face-plates are securely riveted to the auxiliary sills 7 and to the splice-bars 13 of the center sills. Each end platform is carried by the center sills and the two auxiliary sills, and a further function of these 25 auxiliary sills is to transmit part of the end shocks directly to the body-bolsters.

The side stringers 21 partly cover the side sills, being placed externally upon them and supported in position thereon by Z-bars 22, 30 while the intermediate center stringers 23 rest directly on top of the diaphragms and body-bolsters and within the horizontal plane of the side sills and side stringers. In order to hide the side sills as much as possible, 35 they are located inside of the side stringers, and thus the appearance of the car is improved. As will be observed in Fig. 4, the tops of these side sills extend above the tops of the center sills, and thus they are lost within 40 in the side construction of the cars and are given an appearance of less depth than they have in reality and are rendered less conspicuous.

Some of the details of the vestibule are 45 shown in Fig. 1; but as they are of any approved construction their description is deemed unnecessary, and the same is true of the end buffer-plate. Other parts shown and not particularly described may be of 50 usual or approved construction.

As already sufficiently indicated, the invention is not limited to the use of pressed-steel parts or to built-up parts.

While the underframe is especially adapt- 55 ed and designed for passenger-cars, it is also susceptible of adaptation for freight-cars,

and the invention herein claimed is intended to be correspondingly comprehensive.

What I claim is—

1. A metallic underframe, comprising center, side and auxiliary sills connected together transversely, and end sills composed of flanged diaphragms interposed between the various longitudinal sills and secured to them, and provided with top and bottom 60 cover-plates united therewith, the center and auxiliary sills projecting beyond the end sills and adapted to receive a vestibule.

2. A metallic underframe, comprising center, side and auxiliary sills connected together transversely, end sills composed of flanged diaphragms interposed between the various longitudinal sills and secured to them and provided with top and bottom 70 cover-plates united therewith, the center and auxiliary sills projecting beyond the end sills, and face-plates each having front walls 75 provided with inclined ends, a recess to receive the coupling, and top and bottom flanges.

3. A face-plate 12, of pressed steel, having a vertical wall 14 tapering rearwardly and from below upwardly toward its outer ends, a protruding central portion 16 recessed beneath at 17 and having a top flange 19 and a bottom flange 20, and adapted to receive the coupling, the center and auxiliary sills, the vestibule front wall and the steps of a passenger-car.

4. A metallic underframe for cars, comprising center sills, side sills, bolsters, and end sills, framed together, the side sills extending above the level of the center sills and bolsters, and provided with wooden stringers near their upper edges to receive the side 90 framing of the car.

5. A metallic underframe for cars, comprising side sills, center sills, connecting-bolsters, and auxiliary longitudinal sills extending from the bolster outwardly beyond 100 the end sills, and end sills framed in between the longitudinal sills, and a face-plate connected directly to the auxiliary sills and spliced to the center sills.

In testimony whereof I have hereunto set 105 my hand this 4th day of September, A. D. 1902.

ARNOLD STUCKI.
